UNITED STATES PATENT OFFICE.

WILLIAM SHERWOOD, OF BELOIT, WISCONSIN.

MODE OF OPENING AND CLOSING FARM-GATES.

Specification of Letters Patent No. 17,699, dated June 30, 1857.

To all whom it may concern:

Be it known that I, WILLIAM SHERWOOD, of Beloit, in the county of Rock, in the State of Wisconsin, have invented a new and 5 Improved Self-Acting Gate; and I do hereby declare that the following is a full and exact description thereof, reference being had to the accompanying drawings and the letters of reference marked thereon.

10 Figure 1 is a representation of the gate and its machinery drawn in isometrical perspective; (a portion of the top part of the frame H^2 H^3 being removed to show the working parts). A^1 A^2 the posts which support the weight of the gate &c. The distance between these posts A^1 A^2 must be not less than twice the width of the gate way when the gate is open. B a beam connecting the tops of the posts A^1 A^2 having an iron rail 15 C for the wheels D^1 D^2 D^3 D^4 which support the gate E^1 E^2 to roll upon. C an iron rail attached to the beam B and the posts A^1 A^2 . D^1 D^2 D^3 D^4 grooved wheels supporting the gate E^1 E^2 and rolling upon the iron rail C . 20 E^1 E^2 the two parts of the gate which open by sliding apart, being supported by the grooved wheels D^1 D^2 D^3 D^4 which roll upon the rail C . F^1 F^2 F^3 wheels for steadyng the parts of the gate E^1 E^2 and preventing them 25 from moving sidewise. G^1 G^2 G^3 posts holding the wheels F^1 F^2 F^3 which keep the parts of the gate E^1 E^2 in place sidewise. H^1 H^2 H^3 H^4 the frame which holds the machinery for opening and shutting the gate E^1 E^2 . I 30 a roll to which is fastened one end of the chain V which holds the weight W . K a crank for winding up the chain V and rais- ing the weight W . L a roll over which the chain V passes with three or four complete 35 turns to prevent the chain V from moving without turning the roll L . M^1 a crank fast upon the end of the shaft (or axle) which runs through the roll L having an arm M^2 extending in the opposite direction. N a 40 sliding bar which acts as a latch to arrest the motion of the crank M^1 M^2 . O a spiral spring for throwing out the latch N to stop the motion of the crank M^1 M^2 . P a collar fast to the latch rod N for the spring O to 45 press against and the wire Q to pull by. Q a wire connecting the collar P with one end of the lever R . R a lever turning upon the pin a^1 for operating the sliding latch N by means of the wire Q and the collar P . S^1 S^2 50 two links (or braces) connecting the two ends of the lever R with the opposite part of the frame H^2 for the purpose of steadyng the lever R so as to prevent it from being pulled in a wrong direction by the wires T^1 T^2 while these wires may be carried off in a 55 direction diagonal to the plane of motion of the lever R and latch N . These links (or braces) S^1 S^2 are connected to the frame H^2 and the lever R loosely so as to allow of a perfectly free motion of the lever R in its 60 proper directions. T^1 T^2 wires attached to the opposite ends of the lever R to operate the machinery from either of the latch posts U^1 U^2 . U^1 U^2 latch posts from which the machinery for opening and shutting the gate 65 E^1 E^2 is set in motion by any person or carriage approaching or leaving the gateway. These latch posts U^1 U^2 are stationed by the side of the path (or roadway) leading through the gateway, upon the opposite sides of the 70 gate E^1 E^2 and at any convenient distance therefrom. V a chain (or rope) for moving the machinery, by means of the weight W ; one end being secured to the framework H^1 and the other end after passing through the 75 pulley on the weight W and three or four times around the roll L being fastened to the roll I upon which it is wound. The roll L is loose upon its shaft (or axle) and has at one end a ratchet with catch and spring at X . 80 The catch and spring are fastened to the shaft upon which the roll L turns and to which the crank M^1 M^2 is secured in such a manner that the roll L may move in one direction without moving the crank M^1 M^2 85 (to allow the chain V to be wound up on the roll I by means of the crank K) while it can not move in the opposite direction without carrying the crank M^1 with it. Y^1 a connecting-rod from the crank M^1 to one part 90 of the gate E^1 . Y^2 a connecting-rod from one part of the gate E^1 to the lever Z which lever is at its other end connected with the other part of the gate E^2 by the connecting-rod Y^3 . Z a lever turning upon the pin (or 95 fulcrum) a^5 and causing one part E^2 of the gate to open or to shut by the motion of the other part E^1 in the opposite direction, by means of the connecting rods Y^2 Y^3 and the pins a^3 a^4 a^6 a^7 . b a lever attached to the top 100 of the latch-post U^1 having the wire T^1 attached to one end and a cord (or chain) c to the other end. c a cord (or chain) attached to one end of the lever b and passing over the pulley d and hanging down within 105 110

reach of any person approaching or leaving the gate $E^1 E^2$. $d^1 d^2$ pulleys upon the top of the latch-posts $U^1 U^2$. e a ball or ring at the end of the cord (or chain) e . f a stop to prevent the lever b from moving too far. g a treadle at the foot of the latch-post U^2 to the movable end of which is fastened the end of the wire (chain or cord) T^2 after the same has passed over the pulley d^2 and 10 down by the side of the post U^2 . This treadle g is so placed that the wheel or wheels on one side of any carriage approaching or leaving the gate $E^1 E^2$ shall pass over it and press it down and thereby 15 pull the wire (or cord) T^2 to operate the latch N .

Fig. 2 is a vertical section of the frame $H^1 H^2$ taken just behind the lever R and the sliding latch N .

20 Fig. 3 is a vertical section of the frame $H^2 H^2$ taken close to that side on which is the crank K .

Fig. 4 is a horizontal plan of the frame $H^1 H^2$ &c., with its machinery seen from the 25 top.

When any carriage in approaching the gate $E^1 E^2$ passes over the treadle g which extends part way across the carriage road the wheel (or wheels) upon one side of the 30 carriage will press down the treadle g and cause the wire (or cord) T^2 attached to it, to pull the lever R so as to draw back the sliding latch N by means of the wire Q and the collar P . The latch N in sliding back 35 releases the rear end of the crank M^2 which permits the crank M^1 to be set in motion by the weight W operating through the chain V , the roll L &c. which draws back the gate E^1 by means of the connecting rod Y^1 . The 40 motion of one half of the gate E^1 being communicated through the connecting rods $Y^2 Y^3$ and the lever Z &c. to the other half of the gate E^2 causes that to move back in the opposite direction at the same time. 45 When the crank M^1 has made a half revolution it is stopped by the sliding latch N which is thrust forward for that purpose by the spiral spring O pressing against the collar P , as soon as both wheels of the carriage have passed the post U^2 . This holds the 50 gate $E^1 E^2$ open until the carriage has passed through the gateway as far as the post U^1 . Then upon pulling the ball e the sliding latch N will be drawn back as before and the 55 crank M^1 be released to complete its revolution

and close the gate as it is represented in the drawing Fig. 1.

The crank M^1 it will be observed performs its revolutions always in one direction; opening the gate $E^1 E^2$ during one half of the revolution and closing it during the other half of the revolution; being stopped by its extremities M^1 and M^2 alternately striking the sliding latch N . A spring may be placed upon N to prevent the jarring occasioned by the sudden stopping of the crank M ; and another spring may be placed where the end of the chain V , which holds the weight W is fastened to the frame work $H^1 H$, &c., to relieve it from the strain occasioned by the sudden stopping of the weight W whenever the crank $M^1 M^2$ strikes the latch N .

In the drawing Fig. 1 the two latch posts $U^1 U^2$ are represented as being fitted up differently—the one U^1 with a ball or ring to be pulled by hand, and the other U^2 with a treadle to be moved by the wheel or wheels of a carriage—to show that either of these plans or a combination of both of them may 75 be used for setting the machinery in motion as above described for opening and also for shutting the gate $E^1 E^2$.

What I claim and desire to secure by Letters Patent is—

1. The use of the crank $M^1 M^2$ in combination with the latch N or its equivalent and the weight W for the purpose of opening and shutting a sliding gate E^1 in which arrangement the gate E^1 is opened by one half revolution of the crank M^1 , and shut by the other half-revolution of the same; the latch N stopping the crank $M^1 M^2$ at the end of each half-revolution and the whole being set in motion by a weight W which may be wound 90 up when necessary like the weight of a clock.

2. I also claim the arrangement and combination of the lever Z and the connecting rods $Y^2 Y^3$ with the two parts of the gate E^1 and E^2 by means of which one part of the gate E^1 when moving in one direction opens or closes the other part of the gate E^2 by a corresponding motion at the same time in the opposite direction as described in this specification.

WILLIAM SHERWOOD.
